UNITED STATES PATENT OFFICE.

HERBERT S. PULLMAN, OF WATERBURY, CONNECTICUT, ASSIGNOR TO THE SCOVILL MANUFACTURING COMPANY, OF SAME PLACE.

DESIGN FOR A HAMMER FOR BICYCLE-BELLS.

SPECIFICATION forming part of Design No. 26,946, dated April 20, 1897.

Application filed March 1, 1897. Serial No. 625,670. Term of patent 7 years.

To all whom it may concern:

Be it known that I, HERBERT S. PULLMAN, of Waterbury, in the county of New Haven and State of Connecticut, have invented a new 5 Design for a Striker or Hammer for Bicycle-Bells; and I do hereby declare the following, when taken in connection with the accompanying drawings and the letters of reference marked thereon, to be a full, clear, and exact 10 description of the same, and which said drawings constitute part of this specification, and represent, in—

Figure 1, a plan view of a bell striker or hammer embodying my design; Fig. 2, an edge 15 view thereof.

My invention relates to a new and original design for the strikers or hammers of bicycle-bells and the like; and my design consists in

the configuration hereinafter shown and described. 20

My newly-designed striker or hammer is U-shaped, each of its legs being formed with an outwardly-projecting lug or ear, these ears being located opposite each other and being thinner than the legs of which they form a 25 part.

I claim—

The design for a striker or hammer for bicycle-bells, as herein shown and described.

In testimony whereof I have signed this 30 specification in the presence of two subscribing witnesses.

HERBERT S. PULLMAN.
